Des. 234,312
Patented Feb. 11, 1975

234,312

MUSICAL INSTRUMENT CASE

Hari Matsuda, Evanston, Ill., assignor to G. Leblanc
Corporation, Kenosha, Wis.

Filed Oct. 20, 1972, Ser. No. 299,466

Term of patent 14 years

Int. Cl. D3—02

U.S. Cl. D56—1 B

FIG.1

FIG.5

FIG.6

FIG. 1 is a perspective view of a musical instrument case showing my new design;

FIG. 2 is a top view thereof;

FIG. 3 is a bottom view thereof;

FIG. 4 is a front view thereof;

FIG. 5 is a side view taken from the right side of FIG. 4; and

FIG. 6 is a side view from the left side of FIG. 4.

The back side which is not shown is the same as the front side shown in FIG. 4.

I claim:

The ornamental design for a musical instrument case, as shown and described.
